UNITED STATES PATENT OFFICE

WILLIAM T. GREENAN, OF NEW YORK, N. Y., ASSIGNOR OF ONE-HALF TO AUGUST G. REINHARDT, OF NEW YORK, N. Y.

GAME APPARATUS

Application filed July 14, 1931. Serial No. 550,663.

This invention relates to apparatus for playing a novel game.

The apparatus comprises a horizontal grid-like field surrounded on four sides with enclosures, the ends being solid enclosures and the sides preferably slatted or rib-like. The end enclosures have goal baskets supported thereon and the side enclosures are of open grid-like form so as to expose to view the ball adapted to be struck from below the grid-like field in an effort to drive the same into the basket. The entire apparatus is supported on legs and the parts are hingedly connected so that it can be knocked down or collapsed for ease of shipment and also for storage in a limited space when not in use. The various features of the apparatus will be fully apparent from the following specification when read in connection with the accompanying drawings.

In the drawings:—

Fig. 1 is a perspective view illustrating the game apparatus and somewhat diagrammatically showing the ball in play;

Fig. 2 is a plan view of the apparatus;

Fig. 3 is a transverse section on line 3—3 of Fig. 2;

Fig. 4 is a fragmentary longitudinal section on line 4—4 of Fig. 2;

Fig. 5 is a view of the same apparatus in its knocked down or collapsed condition;

Fig. 6 is an elevation of the club.

Referring in detail to the drawings, 10 represents the playing field as a whole. This field, as shown in Fig. 2, is of rectangular shape in plan. The field portion includes longitudinally extending parallel side bars 12—12 and end bars 14—14. Bridging the side bars 12—12 and parallel with the end bars 14—14, there are seventeen cross slats 16 which divide the field into eighteen transversely extending equal divisions 18. The field thus formed has an appearance somewhat like that of a football field, sometimes called a gridiron. This field is supported in a substantially horizontal plane by end members 20—20 having upright legs 22 of such length that the field is about thirty inches from the floor. The end members include solid panel portions 24—24 to which goal bas-

kets 26 and 28, respectively, are secured by hinges 30—30. The panels 24—24 define the ends of the playing area. The sides of the playing area are enclosed by the grid-like members 32—32. Each of these members includes longitudinally extending top and bottom bars 34 and 36, respectively, and upright bars 38 and 40. A plurality of upright slats 42 are supported between the bars 34 and 36, thus forming a substantially transparent or openwork side enclosure for the game apparatus.

In order that the apparatus may be readily collapsed, or knocked down for ease in shipment, or to facilitate storage, the parts are preferably hingedly secured to one another.

As shown in Figs. 3 and 4, the field section 10 is secured to the end members 20 by hinges such as indicated at 44. The side members 32—32 are also hingedly connected to the longitudinal bars 12—12 by hinges 46—46. For detachably holding the side members 32—32 in assembled relationship with the end members 20—20, I provide thumb screws 48—48 which extend through suitable openings in the end members 20—20 and engage threaded fittings secured to bars 34—34 of the side members.

Bridging the space between the legs 32 of each end member, there is a cross bar 50 which is drilled at the top to provide socket 52 for the reception of the vertically disposed portion 54 of a detachable connection member 56, the shank 58 of which is seated in a longitudinally extending member 60. This arrangement permits the member 60 to be readily detached merely by lifting it relatively to the cross bar 50 so as to permit collapsing of the end members 20 against the field portion 10.

The grid-like slat members 32—32 can also be collapsed against the field portion 10 by removing the thumb screws 48 and swinging said side members inwardly about the hinges 46—46. These various hinge connections permit the entire apparatus to be folded into a very compact space, as indicated in Fig. 5. This is advantageous because it facilitates packing and shipping of the article and also

permits the same to be stowed away in a small space, when not in use.

The apparatus can be used for playing games according to various directions, all of the games, however, including the feature of striking the ball X upwardly from below by means of a club or bat C having an angularly disposed portion c. The club is grasped by the player's hand, as indicated in Fig. 1, and the stroke is executed upwardly through the spaces 18 between the slats 16 of the playing field, the object in most of the games played on the apparatus being to cause the ball to fall in either one of the goal baskets 26 or 28. Usually the players stand adjacent the opposite side members 32—32 and take turns striking at the ball. The score is kept and the one making the basket in the fewest number of strokes is the winner. Various penalties may be made for fouls such as striking the ball so hard that it is knocked outside of the apparatus and falls to the floor. Other penalties are imposed when the player attempts to place the ball in a more advantageous position. While not wishing to be limited to any specific rules of play, the following serve as examples for the type of game which may be played on the apparatus.

For one variety of game to be played, the field is marked with red and blue colored areas, as indicated by the shaded portions marked R and B, respectively. On each side of the apparatus, near one end thereof, there is a red area or zone five spaces from the end and there is a blue area six spaces from the end. Near the center of the apparatus, there is a red area opposite the ninth space similarly a blue area opposite the ninth space from the opposite end. The red and blue space mark the zones from which different players are entitled to a free shot in one of the games to be played. In this game, which is for two players, the color nearest the basket to the right of each player denotes the zone or space from which he is entitled to a free shot whenever the ball drops in such zone. But, if a given player touches the ball once with his bat, the opponent has the right to hit the ball. In this game, to begin the play, the players stand on opposite sides in a position sufficiently close to the apparatus to hit the ball by striking upwardly with the club C through the space 18. The ball is dropped by one of the players into the center of the playing field 10 and each player tries either to force the ball into one of his three zones or to shoot the same into the goal basket at his left. After every basket or score is made, the ball is alternately dropped by each player at the center of the field.

The play is limited to five minute halves, the players changing positions between the halves. Each time the player makes a basket, he adds one to his score. Hitting the ball out of bounds, that is, over the top of the

side members 32—32 or over the end members 20—20 entitles the other player to a free shot from the fifth space from the basket at his left. The player having the highest score at the end of two halves wins the game. A tie score necessitates the playing of a third period. 70

The above described game is suitable for two players. As an alternative, another game suitable for play by any number of players will be played as follows;—the ball is dropped in the center of the field 10. The first player strikes the ball upwardly from below the playing field as indicated in Fig. 1, and continues striking the ball until he succeeds in causing it to fall in the basket at his left. The number of strokes which he requires including the successful stroke is his score for his inning. The other players in turn do likewise. In this game, a ball is not to be positioned by the player's hand during the game, but must always be struck from the location where it drops from the field 10. If a player by his hands or otherwise attempts to locate the ball in a more advantageous position, he is penalized by having one point added to his score for each such offense. This penalty is applied regardless of whether he attempts to move the ball with his hands or with the club. When a given player has used one hundred strokes, he drops out and the next player takes his turn. 85

Where a player hits the ball so hard that he knocks it out of bounds or over the sides 34—34 or ends 20—20, he is penalized by adding ten points to his score. The last player wins the game. 90

Various other methods of play may be employed, but it is understood that the above rules and method of scoring are merely illustrative of the character of the game which may be played on the apparatus. Whatever the character of the game, it will be noted that the ball falls or may be dropped on the grid-like playing field. This field being made of spaced slats, it provides sort of a non-rolling field for the ball. That is to say, it provides a surface on which the ball will come to rest in such a way that it cannot roll longitudinally. This of course is apparent because it would have to jump the slats to so roll. Also the weight of the ball is sufficient to prevent it under most conditions from rolling transversely on the slats as a runner, its weight being sufficient to cause the ball to "stay put". The diameter of the ball and the spacing of the slats is such that when the ball comes to rest on its bearing of two adjacent slats, the lower periphery of the ball will lie in a plane below the plane of the slats, thus giving the player an opportunity to use his skill in striking the periphery of the ball at a point best calculated to execute a given shot. 105

The end members 20—20 as shown are 120

preferably solid above the field so as to provide a rebound surface for the ball so that the players may use their skill in making carom shots on the vertical surface in order to successfully shoot the basket. The grid-like side members provide an openwork enclosure which permits visibility and in some styles of game it is contemplated that the player may be permitted to insert the bat or club between the space on the side members defined by the vertical slats 42 although in most form of games, the ball will usually be struck upwardly from below the playing field.

5 Various modifications may be made by those skilled in the art without departing from the invention as defined in the appended claims.

What I claim is:—

10 1. Game apparatus of the character described including a part comprising a plurality of members spaced apart to form a grid-like playing field adapted to provide a non-rolling support for a play ball at many points along the length of said field, there being open spaces between said members to permit striking such play ball upwardly from below the field, an enclosure surrounding the field and goal ball receptacles at opposite ends of the field.

15 2. Game apparatus of the character described including a part comprising a plurality of members spaced apart to form a grid-like playing field adapted to provide a non-rolling support, a play ball adapted to be struck upwardly from below said field, a club having an angularly disposed extremity, said field members being spaced apart to permit the ball to be struck from below by the angular extremity of said club, and elevated goals at opposite ends of the field adapted to catch the ball.

20 3. Game apparatus of claim 2 wherein there are upright side and end enclosures for the field, said goals being supported by the end enclosures.

25 4. Game apparatus of claim 1 wherein the enclosure surrounding the field comprises an upright grid-like side member to permit visibility, and solid upright end members which provide a rebound surface for the ball, the goal receptacles being supported adjacent said end members at a higher elevation than that of said field.

30 5. In witness whereof, I have hereunto signed my name.

WILLIAM T. GREENAN.
